E. E. CLEMENT

RADIO ADVERTISING SYSTEM

Filed Aug. 14, 1922

UNITED STATES PATENT OFFICE.

EDWARD E. CLEMENT, OF WASHINGTON, DISTRICT OF COLUMBIA, ASSIGNOR TO
EDWARD F. COLLADAY, OF WASHINGTON, DISTRICT OF COLUMBIA.

RADIO ADVERTISING SYSTEM.

Application filed August 14, 1922. Serial No. 581,830.

To all whom it may concern:

Be it known that I, EDWARD E. CLEMENT, a citizen of the United States, residing at Washington, in the District of Columbia, have invented certain new and useful Improvements in Radio Advertising Systems, of which the following is a specification, reference being had therein to the accompanying drawing.

10 My invention relates to radio broadcasting systems, and has for its object the production of a system of this type which shall be available for certain classes of advertising and sales work, as well as entertainment. 15 I attain my object by combining, in use, radio transmitting and receiving apparatus with a telephone line or trunks, whereby the radio operator can reach the subscriber over two paths, the subscriber can talk to the radio 20 operator while listening to the broadcasting, and finally the radio operator can connect the subscriber telephonically to the radio transmitter to broadcast the conversation. This combination gives in effect a complete 25 communicating circuit made up of outgoing wave radiation and incoming or return wire conduction, the latter serving to localize and fix the former.

My invention is illustrated in the accompanying drawing in which the figure is a diagram of telephone circuits with the radio broadcasting and receiving apparatus and circuits applied thereto.

Referring to the drawing, A is a subscriber's telephone station having line wires 16—17 connecting it to terminals of a telephone switchboard in a central station C. A² is another telephone station connected to the telephone central station C by trunks 55—56 which may for present purposes be considered line wires. At the station A I provide a radio receiving set A' having the usual aerial or loop antenna and transformer 35 on the output side for connection to a loud speaker 36, and energizing batteries A₁ and B₁. As supervision is desired over this instrument, I provide it also with a telephone transmitter T' and a standard common battery talking circuit 59—60—

61—62—63, terminating on clips 64—65 or 50 other convenient attaching devices which may be applied to the ordinary telephone terminals at station A. Condensers q' and q^x normally prevent the flow of battery current in these circuits. A switch H² is provided for closing the transmitter T to line and also bridging the wires 57—58 of the loud speaker across the line. As shown, the same switch serves to close the filament circuit through battery A₁, but the two elements of the switch may be made separate, so that either the filament circuit or the telephone circuit may be closed separately.

At the station A², multiple jacks J^x are provided for the trunks or lines 55—56 if 65 a separate radio switchboard is employed, or as an alternative, ordinary jacks or line terminals J² may be made accessible to the radio operator. Taking the jacks as typical of any convenient connective terminals, the 70 operator at the radio switchboard may connect the line 55—56 through a suitable amplifier to the broadcast transmitter T, or may connect said wires 55—56 through a cord circuit or a suitable switch to his own telephone, not shown. I have indicated a key K in the operator's cord circuit for this purpose.

The operation of the system is as follows: Assuming the station A² to be that of an 80 advertiser, such as a firm engaged in the sale of musical instruments, the radio set A' is connected at the station of a subscriber whom it is desired to interest, or who may be willing to cooperate in advertising the 85 product. A regular program or test operation may then be given, using ordinary and well known transmitters, amplifiers, etc., for this purpose, typically indicated at T². During this performance the radio operator 90 has control over the telephone line which is supposed to be connected up as shown in the drawing. Switch H² being closed at the substation, the operator can connect himself through key K and listen in 95 on the circuit 57—58 at station A'. By means of his own telephone he may also speak through the broadcast transmitter T

so that the subscriber at A' as well as others who are listening in can hear him. Finally, he is able to receive responses from the subscriber at A' through the telephone T' and the telephone circuit 16—17, 55—56, and this circuit may be connected to the broadcast transmitter T for the purpose of broadcasting the communication received.

I claim:

10. 1. A system of the class described comprising a broadcasting station and a radio receiving station, with a telephone circuit to connect the same for telephonic communication therebetween, and means for connecting the telephone circuit at either station to the radio circuits, said means comprising a telephonic connection from the output side of the radio receiver to the telephone circuit and a connection from the telephone circuit to the input side of the radio circuit at the broadcasting station, whereby the radio receiver may be supervised from the broadcasting station, and telephone messages from the radio receiving station may be broadcasted.
15. 2. The system claimed in claim 1, with a separate telephone transmitter connected to and forming part of the radio receiving apparatus at the substation and supplied with current over the telephone circuit.
20. 3. A system of the class described comprising a broadcasting station and a radio receiving station, with a telephone circuit connecting the same for telephonic communication therebetween, the apparatus at said receiving station comprising a detector set, a receiver therefor, and a telephone transmitter, with means to connect said radio receiver and said telephone transmitter to said telephone circuit so that both direct transmission of original voice waves and repeated transmission of sounds received through the detector set may be effected over said telephone circuit.
25. 4. A system of the class described comprising a broadcasting station and a radio receiving station, with a telephone circuit connecting the same for telephonic communication therebetween, the apparatus at said receiving station comprising a radio receiver and a telephone transmitter, with means to connect said radio receiver and said telephone transmitter to said telephone circuit so that both direct transmission of original voice waves and repeated transmission of sounds received through the radio receiver may be effected over said telephone circuit, together with a telephone receiver connected to and forming part of said radio receiver, and means to connect said radio receiver also to the telephone line for the telephonic receiving of audio frequencies thereover.
30. 5. A system of the class described comprising a telephone central station and a

subscriber's station, with the telephone line circuit interconnecting them; said subscriber's station equipment comprising a telephone transmitter, a telephone receiver, connections therefrom to the telephone line, a radiophone receiver adapted to take in high frequency radio waves on its input side, and connected on its output side to said telephone receiver, whereby for audio waves the radiophone and the telephone are connected in common to the telephone line.

6. A system of the class described comprising a telephone central station, a plurality of subscribers' stations, line circuits interconnecting them, a source of common battery supply at the central station feeding current to said subscribers' stations through said line circuits, and the combined telephone and radiophone receiver at subscriber's station comprising the following instrumentalities: a telephone receiver adapted to be connected to the line to receive audio frequency or telephone waves thereover, a radio receiving and detecting set adapted to take in radio waves on its input side and on its output side having connection for audio transmission to said telephone receiver.

7. A system of the class described comprising a telephone central station, a plurality of subscribers' stations, line circuits interconnecting them, a source of common battery supply at the central station feeding current to said subscriber's station through said line circuits, and the combined telephone and radiophone receiver at subscriber's station comprising the following instrumentalities: a telephone receiver adapted to be connected to the line to receive audio frequency or telephone waves thereover, a radio receiving and detecting set adapted to take in radio waves on its input side and on its output side having connection for audio transmission to said telephone receiver, and an operative or connection also to the telephone line.

8. In a system of the class described comprising means for telephonic or audio frequency transmission between two stations, and means for high frequency or radio transmission between the same stations, a receiving station equipment including telephone transmitter and receiver connected to the telephone line, a radiophone receiver having high frequency input and low or audio frequency output, with a step down transformer coupling connecting the output side with the telephone receiver.

9. In a system of the class described comprising means for telephonic or audio frequency transmission between two stations, and means for high frequency or radio transmission between the same stations, a receiving station equipment including tele-

phone transmitter and receiver connected to the telephone line, a radiophone receiver having high frequency input and low or audio frequency output, with a step down 5 transformer coupling connecting the output side with the telephone receiver, and the audio or telephone line circuit.

10. In a system of the class described comprising means for telephonic or audio frequency transmission between two stations, and means for high frequency or radio transmission between the same stations, a receiving station equipment including telephone transmitter and receiver connected to 15 the telephone line, a radiophone receiver having high frequency input and low or audio frequency output, with a step down transformer coupling connecting the output side with the telephone receiver, and the 20 audio or telephone line circuit in parallel, whereby an operator at the transmission end of the line can listen in on the radio receiver at the receiving end, and can transmit and receive at audio frequencies directly to and 25 from said radio receiving station.

11. A combined telephone and radiophone receiving station comprising a telephone transmitter and a telephone receiver with means for connecting the same to a physical 30 telephone line, a radiophone receiver having high frequency input and low frequency output and connected on the output side to said telephone receiver, a source of current supply for said telephone transmitter, a source 35 of current supply for said radiophone receiver, and common switching means controlling the connection of said source of current.

12. A combined telephone and radiophone 40 receiving station comprising a telephone transmitter and a telephone receiver, with means for connecting the same to a physical telephone line, a radiophone receiver having high frequency input and low frequency output and connected on the output side to 45 said telephone receiver, a source of current supply for said telephone transmitter, and a source of current supply for said radiophone receiver, together with means actuated 50 in the operation of said connecting means for the telephone instrument, to close the current supply circuit for the radiophone.

13. A system of the class described comprising a plurality of telephone subscribers' 55 stations, a central station, telephone line circuits interconnecting said subscribers' stations and the central station, a switchboard at the central station for inter-connecting subscribers' lines for conversational purposes, combined radiophone and telephone 60 equipment at subscribers' stations connected in common to their individual telephone lines leading from the central station to said subscribers' stations, and a central office broadcasting station equipped with both telephone 65

instruments and radiophone broadcasting means adapted to operate in conjunction with said subscribers' instruments, a telephone line circuit connecting said broadcasting station with said telephone central 70 station and the switchboard thereat, and means for connecting said line circuit from the broadcasting station through said switchboard to a subscriber's line, the equipment at said broadcasting station being so arranged that the broadcasting operator may receive and transmit from and to both the radiophone and the telephone apparatus at subscriber's station over the connected telephone circuits without using any other than 80 audio currents for which the said circuits are designed, and can also communicate directly with said subscriber's station by radio transmission, while using the telephone circuits for supervision. 85

14. A radiophone exchange system comprising a radiophone central station, a radio switchboard, amplifying and transmitting means, and telephone instrumentalities for all purposes, at said radio central station, 90 subscribers' stations each equipped with a radiophone receiving device adapted to respond to radio waves transmitted from said radio central station, audio receiving means at each subscriber's station, a telephone system comprising a central station and subscribers' lines extending therefrom to telephone instruments at the subscribers' stations and circuit connections from said audio receiving means at the radiophone subscribers' 95 stations to individual telephone lines, with means for connecting the switchboard at the radio central station through the telephone central station with said individual telephone lines selectively. 100

15. A radiophone exchange system comprising a radio central station, with transmitting means thereat, radio subscribers' stations adapted to receive waves transmitted from the central station, telephonic transmitting and receiving apparatus at said radio central station, a telephonic transmitting and receiving apparatus at each substation, a plurality of telephone lines and a telephone central station with means thereat for interconnecting said lines, and a common connection from the radiophone receiver and the telephonic apparatus at each radiophone subscriber's station, to a telephone line, and means controllable at the 110 radiophone central station to connect the same with any of said telephone lines. 115

16. The combination of a plurality of substations, a central station, a radio broadcasting station and broadcasting apparatus 120 thereat, a radio receiver at each substation, a wire line connecting each substation with the central station, a wire line connecting the broadcasting station with the central station, means at the central station for con- 125 130

necting a substation with the broadcasting station, between said substation and the station for conversation through said wire lines, means also at said central station 10 supplying energy to the radio receiver at the substations over said wire lines, and means at the broadcasting station for operatively extending said conversational con-
